CLAIM

The ornamental design for a cluster controller for Input/Output subsystem, as shown and described.

DESCRIPTION

FIG. 1 is a top, right side perspective view of a cluster controller for Input/Output subsystem showing our new design;

FIG. 2 is a rear elevational view thereof on an enlarged scale;

FIG. 3 is a front elevational view thereof on an enlarged scale;

FIG. 4 is a left side elevational view thereof on an enlarged scale, the right side being a mirror image;

FIG. 5 is a top plan view thereof on an enlarged scale;

FIG. 6 is a bottom plan view thereof on an enlarged scale.

FIG. 1

FIG. 2

FIG. 3

FIG. 4

FIG. 5

FIG. 6
